(57) **CLAIM**

The ornamental design for a plurality of contact fields for a printed circuit board, as shown and described.

DESCRIPTION

FIG. 1 is a top perspective view of a plurality of contact fields for a printed circuit board, showing our new design; FIG. 2 is a bottom perspective view thereof; FIG. 3 is a front elevation view thereof; FIG. 4 is a rear elevation view thereof; FIG. 5 is a right elevation view thereof; FIG. 6 is a left elevation view thereof; FIG. 7 is a top plan view thereof; FIG. 8 is a bottom plan view thereof; FIG. 9 is a bottom perspective view of thereof, shown enlarged; and, FIG. 10 is a bottom elevation thereof, shown enlarged. The equal-length broken lines depict environmental subject matter that forms no part of the claimed design.
